[57] **CLAIM**

The ornamental design for a bed, as shown and described.

DESCRIPTION

FIG. 1 is a perspective view of a bed showing my new design;

FIG. 2 is a front elevational view thereof; and,

FIG. 3 is a side view thereof, the opposite side being a mirror image of the side shown.

The rear of the footboard is identical to the front of the footboard shown in FIGS. 1 and 2.
